TABLE FOR READING BLUEPRINTS OR THE LIKE

Robert S. Collins, Downey, and Francis G. Parkison,
Los Angeles, Calif.

Application May 14, 1953, Serial No. 25,005

Term of patent 3½ years

(Cl. D33—14)

To all whom it may concern:

Be it known that we, Robert S. Collins and Francis G. Parkison, citizens of the United States, residing in Downey and Los Angeles, respectively, in the county of Los Angeles, State of California, have invented a new, original, and ornamental Design for a Table for Reading Blueprints or the like, of which the following is a specification, reference being had to the accompanying drawings, forming a part thereof.

Figure 1 is a top plan view of a table for reading blueprints or the like, showing our new design.

Figure 2 is a side elevational view thereof;

Figure 3 is a sectional view thereof taken on the line 3—3 of Figure 2;

Figure 4 is an end elevational view thereof; and

Figure 5 is a sectional view thereof taken on the line 5—5 Figure 2.

We claim:

The ornamental design for a table for reading blueprints or the like, as shown.
